METHOD OF SEPARATING BLANKS FROM
SHEET MATERIALArthur J. Evers, Westerly, R. I., assignor to C. B.
Cottrell & Sons Company, Westerly, R. I., a
corporation of Delaware

Application November 18, 1937, Serial No. 175,287

4 Claims. (Cl. 164—18)

The object of my invention is to provide a simple, efficient, and inexpensive method whereby blanks of predetermined contours may be separated by pressure from sheet material.

5 The object of my invention, more specifically, is to provide a novel method for separating by pressure, in a single operation, garment blanks from a sheet of fabric whereby the blanks for a complete garment or suit may be separated from 10 the sheet of garment fabric at a single operation.

My invention includes the use of removable skeleton frames, shaped to predetermined contours, said shaped frames having dull operating surfaces and being associated with the sheet material, pressure being exerted on said associated sheet material and frames between relatively movable elements for causing the separation of the blanks from their sheet material by said shaped frames.

20 An apparatus for carrying out my method is represented in the accompanying drawings, in which

Fig. 1 represents the apparatus in side elevation with the movable parts in the positions they assume when the reciprocating bed is about to start on its forward movement through the pressure rolls, the lifting bracket for handling the upper pressure plate being shown in its raised position;

30 Fig. 2 represents a top plan view of the apparatus;

Fig. 3 represents a longitudinal vertical section taken in the plane of the line III—III of Fig. 2, looking in the direction of the arrows;

35 Fig. 4 represents an end view of the apparatus, the lifting bracket being shown in full lines in its raised position, and in dotted lines in its lowered position;

Fig. 5 represents an enlarged detail section 40 showing the upper and lower pressure plates with the interposed sheet material and shaped wire before pressure has been applied thereto;

Fig. 6 represents a similar section after the pressure has been applied to cause the shaped 45 wire to separate the blank from the sheet material;

Figs. 7 and 8 represent detail cross sections through other forms of wire; and

50 Figs. 9 and 10 represent plan views of one of the shaped wires and the blank which was separated thereby from the sheet material.

The sheet material from which the blanks 1 are separated is denoted by 2. The skeleton frame for separating the blanks from the sheet 55 material is herein shown as a wire 3 bent to the

predetermined contour, the ends of the wire being preferably permanently united, as by welding. The shaped wire has a dull sheet material engaging surface 4 and the wire may be of any desired cross sectional form. For instance, in 5 Figs. 5 and 6, I have shown a wire as elongated in cross section with convex top and bottom edges. In Fig. 7, I have shown a wire round in cross section, and in Fig. 8, I have shown a wire having a flat upper surface and a convex lower 10 or sheet material engaging surface.

Two elements, in the present instance, upper and lower pressure plates 5 and 6 have plane surfaces which are arranged to receive between them the shaped wire 3 and the sheet material 2. 15

Suitable means may be provided for exerting pressure on the upper and lower plates 5 and 6 sufficient to cause the shaped wire to separate the blank 1 from its sheet material 2. The means herein shown comprises an apparatus which is 20 constructed, arranged, and operated as follows:

The sides 7 and 8 of the frame uprise from a suitable base 9. The upper and lower pressure rolls 10 and 11 are rotatably mounted in sliding and fixed bearings respectively, in the side frames 25 7 and 8. The upper pressure roll 10 may be positively driven from a reversing motor 12 mounted on the base 9 of the frame, through a train of gears 13, 14, 15, 16, 17, 18. The lower pressure roll 11 may be positively driven from the shaft 30 of the gear 15 through gears 19, 20.

The reciprocating bed is denoted by 21 and it may be positively driven from the shaft of the lower pressure roll 11 at the opposite side of the frame through gears 22, 22 on the shaft of the 35 pressure roll 11 and racks 23, 23 carried by the bed 21. This bed may be supported on the usual banks of rollers 24, 25 located at the front and rear of the pressure rolls 10 and 11. Hold-down rollers 26, 26 may be provided for the reciprocating bed.

The upper pressure roll 10 may be adjusted toward and away from the lower pressure roll 11, as, for instance, by a hand wheel 27 carried by a cross shaft 28 which has beveled gear connections 29, 30 with vertical shafts 31, 31 provided with screw threaded portions engaging the sliding bearings 32, 32 of the upper pressure roll 10. 45

The means which I have shown for raising and lowering the removable upper pressure plate 5 is 50 as follows:

A longitudinally disposed rock shaft 33 is mounted in a frame 34 carried by the reciprocating bed 21, which rock shaft is located outside the side frame 8 and beyond the gearing 30 that 55

it will not interfere with the same in the reciprocation of the bed.

5 A pair of uprising arms 35, 35 of a swinging bracket is fixed to this rock shaft 33, each of which arms carries a pair of manually operated hooks 36, 37, yieldingly connected by a divided rod 38. An operating handle 39 is carried by the hook 36 for bringing the hook into and out of engagement with the side edges of the removable upper pressure plate when the bracket is swung down across the bed.

10 A counterweight 40 may be provided on the rock shaft 33 for counterbalancing the weight of the upper pressure plate 5 when it is engaged and held by the plate lifting bracket.

15 In operation: Let it be assumed that a plurality of separate wires have been bent to predetermined contours. The sheet of material, fabric, if blanks for clothing are to be produced, 20 is placed on the lower pressure plate 6 which may, if so desired, form a part of the reciprocating bed. The shaped wires are then placed in the desired arrangement upon the sheet of material. The upper pressure plate 5 which has 25 been carried by the swinging bracket is then lowered onto the shaped wires and sheet material. The hooks 36 and 37 of the swinging bracket are then operated to release the bracket from the upper pressure plate. The bracket is 30 then swung to its raised position. The bed may then be advanced to pass the pressure plates and interposed sheet material and shaped wires, through the pressure rolls 10 and 11, thereby causing the shaped wires to separate the blanks 35 from the sheet material by pressure and at a single operation.

When the bed reaches the end of its forward movement the swinging bracket may be lowered and its hooks caused to engage the side edges 40 of the upper pressure plate. The said plate is then removed by swinging the bracket to its raised position. The shaped wires, the blanks and the blanked-out sheet material may then be removed from the lower plate. The bed with 45 the lower plate and the raised bracket with the upper plate may then be returned to their original positions, ready for the next operation.

50 From the above description it will be seen that I have provided a simple, inexpensive and efficient method for blanking out sheet material and that I am enabled by said method to separate by pressure, in a single operation, the blanks necessary to produce a garment or suit from a sheet of clothing fabric.

It will also be seen that by using shaped wires with dull sheet material engaging surfaces no sharpening of the surfaces is required as in the case where hardened dies with sharp cutting edges are provided for cutting the blanks from 5 the sheet material.

What I claim is:

1. The method which comprises associating two elements with interposed sheet material and a frame shaped to a predetermined contour, 10 advancing the two elements with the interposed sheet material and frame through a pressure means sufficient to cause the frame to separate a blank from the sheet material, removing one of the elements, the frame, the blank and the 15 blanked-out material, and returning the other element through the pressure means and the removed element around the pressure means.

2. The method which comprises associating two elements with interposed sheet material and 20 frames shaped to predetermined contours, advancing the two elements with the interposed sheet material and frames through a pressure means sufficient to cause the frames to separate blanks from the sheet material, removing one of 25 the elements, the frames, the blanks and the blanked-out material, and returning the other element through the pressure means and the removed element around the pressure means.

3. The means which comprises associating 30 two elements with interposed sheet material and a wire bent to a predetermined contour, advancing the two elements with the interposed sheet material and wire through a pressure means sufficient to cause the wire to separate a blank 35 from the sheet material, removing one of the elements, the wire, the blank and the blanked-out material, and returning the other element through the pressure means and the removed element around the pressure means.

4. The method which comprises associating 40 two elements with interposed sheet material and a plurality of wires bent to predetermined contours, advancing the two elements with the interposed sheet material and wires through a pressure means sufficient to cause the wires to separate blanks from the sheet material, removing one of the elements, the wires, the blanks and the blanked-out material, and returning the other element through the pressure means and 45 the removed element around the pressure means.

ARTHUR J. EVERSON.
